To all whom it may concern:

Be it known that I, Donald C. Miller, a citizen of the United States, residing at Paterson, in the county of Passaic and State of New Jersey, have invented a new, original, and ornamental Design for Decorative Paper or Similar Article, of which the following is a specification, reference being had to the accompanying drawing, forming a part thereof.

The design consists of a series of bands of varying tonal density on a corrugated background,

said bands being separated by narrow stripes of contrasting color, and arranged so that the tonal density decreases from the edges toward the middle as shown.

In the drawing:

The figure is a plan view of a piece of decorative paper showing the design.

I claim:

The ornamental design for decorative paper or similar article, as shown and described.
